US00D363918S

United States Patent [19]

Buongervino et al.

[11] Patent Number: Des. 363,918

[45] Date of Patent: **Nov. 7, 1995

[54] CABLE INTERFACE ASSEMBLY

[75] Inventors: **Nicholas Buongervino**, Hauppauge; **Ronald Edwards**, Sayville; **Peter Musteric**, Hauppauge; **Patrick Mauro**, Lake Grove, all of N.Y.

[73] Assignee: **Symbol Technologies, Inc.**, Bohemia, N.Y.

[**] Term: 14 Years

[21] Appl. No.: 37,880

[22] Filed: Apr. 21, 1995

[52] U.S. Cl. D13/147

[58] Field of Search D13/146, 147; D14/114, 107; 439/620, 638, 639; 361/683

[57] CLAIM

The ornamental design for a cable interface assembly, as shown and described.

DESCRIPTION

FIG. 1 is a top, front, left-side perspective view of a cable interface assembly showing our new design;

FIG. 2 is a top plan view thereof;

FIG. 3 is a left-side elevational view thereof;

FIG. 4 is a front elevational view thereof;

FIG. 5 is a right-side elevational view thereof;

FIG. 6 is a rear elevational view thereof; and,

FIG. 7 is a bottom plan view thereof.
